UNITED STATES PATENT OFFICE.

CHARLES WIRTH, OF SCRANTON, PENNSYLVANIA.

CRUDE-OIL BURNER.

1,138,165.

Specification of Letters Patent.

Patented May 4, 1915.

Application filed July 25, 1914. Serial No. 853,214.

To all whom it may concern:

Be it known that I, CHARLES WIRTH, a citizen of the United States, residing at Scranton, in the county of Lackawanna and 5 State of Pennsylvania, have invented new and useful Improvements in Crude-Oil Burners, of which the following is a specification.

This invention relates to crude oil burners, 10 and more particularly to that type wherein the crude oil is vaporized and mixed with oxygen before entering the burner tube.

The primary object of the invention is the provision of a burner wherein the crude oil 15 is vaporized and then passed through an air chamber where on leaving it is mixed with an increased admission of compressed air, thus producing a perfect non-luminous flame which is emitted with considerable 20 force at the outlet of the burner tube.

With these and other objects in view the invention consists in the construction, combination and arrangement of parts as will be hereinafter more fully described, illustrated in the accompanying drawings and 25 pointed out in the claims hereunto appended.

Referring to the drawings:—Figure 1 is a side elevation. Fig. 2 is an enlarged longitudinal section through the burner. Fig. 3 is a top plan view thereof. Fig. 4 is a section on the line 4—4 of Fig. 2. Fig. 5 is a section on the line 5—5 of Fig. 2. Fig. 6 is a section looking in an opposite direction.

Similar reference characters indicate corresponding parts throughout the several views in the drawings.

Referring to the drawings by numerals, 1 designates a cylindrical burner tube opening 40 into the atmosphere at one end and having its remaining end closed by a plate 2, the said plate being provided with a circular series of openings adjacent its peripheral edge. The plate 2 is provided with a concentrically arranged boss 3, and passing 45 through the boss and plate is a passage 4 flared in opposite directions from a point intermediate of its ends. Having screw threaded engagement with the boss 3 is a 50 casing 5 forming an air chamber 6 and is provided with a pair of right angular arranged screw threaded openings 7 and 8. Threaded into the opening 7 is a reducing nozzle 9 having a bore 10 of different diameters, one end of said bore communicating

with the passage 4 through a series of small apertures 11 which have their axes disposed at an angle to the axis of the bore 10, while an oil vapor pipe 14 communicates with the remaining end.

An oil pipe 12 leads into one arm of a T-coupling, the other arm being connected by a solid plug to a second T-coupling. An oil pipe 13 leads from the first coupling to the worm 15, and an oil vapor pipe 14 leads 65 from the worm to the second coupling, the latter having a connecting pipe section leading to the bore 10.

Connected to the casing 5 by a plug 16 having screw threaded engagement with the 70 opening 8, is an air pipe 17 having communication at one extremity with a source of air under pressure and at its remaining extremity with the air chamber 6. A valve 18 is provided for controlling the amount of air 75 fed to the flame, a channel 19 being provided between the head 20 of the reducing nozzle 9 and the wall of the passage 4 for allowing the air in the chamber 6 to mingle with the oil vapor.

A stand 21 formed of metal pipes is provided when the heater is stationary for any length of time, as when the process of heating heavy shafting and expanding hubs of 80 wheels.

The device is attached to a tank containing crude oil, naphthas, oil of tar, vegetable oils or waste lubricating oil and this product is forced with compressed air, of about 25 pounds pressure, into the pipe 12, thence 90 through the pipe around the casing 5 into the worm 15 then back to where the pipe 12 communicates with the nozzle 9. In the reducing nozzle the oil is reduced to a fine stream and is forcibly thrown through the 95 apertures 11 into the interior of the burner tube 1 in the form of a fine spray. This fine spray is ignited and as the worm 15 becomes heated, the oil which passes through it is heated thus forming a gas, which returns to 100 the nozzle 10 and mixes with the auxiliary air where the channel 19 meets the apertures 11 and as a result of the proper feed of oxygen a perfect non-luminous flame is emitted with considerable force at the outlet of the burner tube.

If found necessary a check valve can be positioned in the oil pipe between the burner and the oil tank for preventing back flow of gas or oil.

Having thus described the invention, what I claim is:—

1. In a burner of the class described comprising a casing having three screw threaded outlets, a cylindrical burner tube open at one end, a plate closing one end of said burner tube having screw threaded engagement with one of the outlets, said plate having a passage flared in opposite directions from a point intermediate of its ends, a reducing nozzle having a bore of different diameters, screwed into another of the outlets, the bore of said nozzle communicating with the passage of said plate, an oil pipe communicating with the bore of said nozzle, and an air pipe communicating with the interior of said casing, through the remaining outlet.
2. In a burner of the class described, comprising a casing having three screw threaded outlets, a cylindrical burner tube open at one end, a plate closing one end of said burner tube having screw threaded engagement with one of the outlets, said plate having a passage flared in opposite directions from a point intermediate of its ends, a reducing nozzle having a bore of different diameters screwed into another of the outlets, a conical head on said nozzle having its outer surface spaced from the wall of the passage in the said plate for forming an intervening channel, the bore of said nozzle communicating with the passage of said plate, through a series of angularly disposed apertures, the outlet of the channel being disposed adjacent the outlets of the apertures, an oil pipe communicating with the bore of said nozzle, and an air pipe communicating with the interior of said casing, through the remaining outlet.
3. In a burner of the class described, comprising a casing having three screw threaded outlets, a cylindrical burner tube open at one end, a plate closing one end of said burner tube having screw threaded engagement with one of the outlets, said plate having a passage flared in opposite directions from a point intermediate of its ends, a reducing nozzle having a bore of different diameters, screwed into another of the outlets, a conical head on said nozzle having its outer surface spaced from the wall of the passage in the said plate for forming an intervening channel, the bore of said nozzle communicating with the passage of said plate, through a series of angularly disposed apertures, the outlet of the channel being disposed adjacent the outlets of the apertures, an oil pipe communicating with the bore of said nozzle, and an air pipe communicating with the interior of said casing, through the remaining outlet.

In testimony whereof I affix my signature in presence of two witnesses.

CHARLES WIRTH.
